UNITED STATES PATENT OFFICE.

WILBUR H. PECK, OF LOS ANGELES, CALIFORNIA.

CENTRIFUGAL CONCENTRATOR.

1,395,517.

Specification of Letters Patent.

Patented Nov. 1, 1921.

Application filed November 23, 1920. Serial No. 426,047.

To all whom it may concern:

Be it known that I, WILBUR H. PECK, a citizen of the United States, residing at Los Angeles, in the county of Los Angeles and State of California, have invented certain new and useful Improvements in Centrifugal Concentrators, of which the following is a specification.

My invention relates to improvements in concentrating machines in which centrifugal and coördinating liquid separating forces are employed to effect separation and bedding of concentrates through use of a rapidly rotatable concentrating vessel or member, and a relatively differentially rotatable core member, as hereinafter explained, and the main objects of my invention are not only directed to more economical and stable structure but to higher and more efficient results in concentration.

I attain these objects by the mechanism and means which are herein explained and which I have illustrated in the accompanying drawings, of which

25 Figure 1 is partly a side elevation and partly a vertical central longitudinal section of my improved concentrating machine.

Fig. 2 is partly a central longitudinal vertical section and partly a side elevation of my concentrator, although not showing the outer journal bearing or feed member, and with the concentrating vessel, and interposed discharge ring, detached relatively and from the supporting head, the two former being 35 moved longitudinally from their places.

Fig. 3 is a transverse vertical section of Fig. 1 on line 3—3 of Fig. 1, looking in the direction of the arrows.

Fig. 4 is a central vertical longitudinal section of the core member shown removed from its supporting shaft, having been withdrawn longitudinally therefrom.

Fig. 5 is a side elevation of the end of the core supporting shaft, which engages the core, also showing the adjacent part of the shaft.

Fig. 6 is partly a longitudinal central section and partly an elevation of a broken relatively assembled detail of a portion of 50 the core supporting shaft, part of the hollow vessel supporting shaft and some other parts.

Fig. 7 is partly a section and partly an elevation of a portion of the core shaft draw mechanism and a portion of such shaft, enlarged.

In making my improved centrifugal concentrator, I provide a rotatable concentrating vessel which is shown in the drawings in a horizontal position. This vessel as a concrete whole embodies a circumferential wall 60 or tube portion, two end or head portions and a chambered discharge ring portion, the latter interposed between the larger head and tube portions, as hereinafter explained.

The tube portion 2, is preferably somewhat conical shaped, as illustrated, and is provided with a flange 3, at its large end, through which it is securely and concentrically but removably fastened to its larger head 4, by means of bolts 5, passing through the interposed chambered ring 6, as shown in Fig. 1. The individuality of these several parts is best illustrated in Fig. 2 of the drawings, where they are shown moved apart. The ring 6, also serves as means 75 through which material is discharged from the vessel and I will therefore call it a discharge ring.

The head 4, is provided with a central hub 7, which is rigidly mounted on the extended 80 end of a hollow shaft 8, which shaft is rotatably journaled in boxes 9 and 10, and may be rotated by means of a belt pulley 11, from any suitable prime mover, so when the shaft 8 is revolved, the head is also revolved, carrying with it in rotation the concentrating vessel. The journal boxes 9 and 10 are carried on the upper ends of stands 12 and 13, which are mounted on the base plate 14 of the concentrator.

90 The smaller end of the vessel is provided with an end or head 15, which may be secured to the vessel by screws 16, as illustrated in the drawings, and near the central portion of this head there is provided an outwardly extended hollow trunnion 17, having an opening 18, at its central part through which feed of material for separation and water may be introduced into the vessel.

This trunnion 17 serves as a journal bearing 100 for the outer end of the vessel and is mounted in a journaled box 19, supported on a stand 20, which is secured at its base to the bed plate of the concentrator.

There is provided a circumferential row 105 in the discharge ring 6, of the vessel, of short nipples or pipes 21, having small discharge holes or openings 22, through which material and water fed into the vessel during operation, may be discharged.

Around the vessel, encircling the discharge ring is a hollow hood or launder, 23, with a suitable annular crack or opening 24, on its inner circumference, positioned in radial alignment with the discharge holes 22, from the vessel, so that water and material discharged from the vessel through these holes will be thrown through the opening 24, into the launder, as indicated by the arrows in Fig. 1 and be carried down to the lower part of the launder and passed out of its extended part 25, and also indicated by the arrows at their point.

The launder is separable at the lines 26, Fig. 3, the parts, being provided with ears 27, which are fastened together by bolts 28, thereby holding the two parts of the launder as a single unit. The launder is held to place on the base plate of the concentrator by a maintaining part 29.

To operate inside of the vessel for purposes of forming with the inner wall of the vessel a separating channel 30, and also to serve as means for affecting a scrubbing wash within such channel to assist in separating and moving to discharge the substance not desired to be retained as concentrates, while bedding the concentrates in the vessel, I provide a core 31, which in Fig. 1 is partly illustrated in section, and in Fig. 2 is shown in outside elevation. In Fig. 4, the core is also shown in section.

The circumferential surface of this core member is preferably substantially the same shape as the internal bore of the vessel, but somewhat smaller in diameter than such bore, and is sufficiently shorter than the internal length of the vessel, to enable it to be traveled longitudinally in the vessel, to the extent desired for purposes hereinafter explained.

The core is smooth on its circumferential surface and is of diameter to leave a comparatively small space 30, between its circumferential exterior and the surface 32, of the interior wall of the vessel, as illustrated in Figs. 1 and 3, the space 30 constituting the separating channel and the surface 32, forming the separating surface, on which the separated concentrates become bedded.

The core member has its ends somewhat depressed or hollowed out, as illustrated in Figs. 1 and 4, and its ends are provided with metal plates 33 and 34, respectively, which serve to protect the ends of the core from serious wear.

The core is also provided with a sleeve portion 35, located longitudinally and centrally therein, and the core is securely but removably mounted within the vessel on the extended end part of a central shaft 36, which end part passes through the sleeve 35, while the central portion of the shaft 36 passes through and is rotatably journaled

in the hollow of the vessel supporting shaft 8. The outer end of the shaft 36, is journaled in a box 37 as illustrated. It is provided with a pulley 38, by means of which the shaft with the core may be rotated at the rate of speed desired.

The end portion of the shaft 36, which extends into the vessel, as above stated, passes through the longitudinally positioned sleeve 35, in the central part of the core, so that the shaft securely and rigidly supports and carries the core, while this end of the shaft preferably terminates within the vessel.

The nut 39, serves to assist in rigidly holding the core on this end of its shaft, although the core may be longitudinally withdrawn and removed from the shaft, by removing the nut, when the wall or shell portion 2, of the vessel is removed, as shown in some of the drawings, while at the same time maintaining journaled placement of its shaft 36.

It will be seen that by this arrangement, as the shaft 38 is revolved the core is also revolved, such motion being independent of the rotation of the concentrating vessel.

As means for supplying material for separation, mixed with water into the vessel, which mixture I will term as a pulp, I provide a suitable feed pipe 39', having a valve 40, and with one part of the pipe 41, extending through the central opening 18, in the journal trunnion of the small end of the vessel, as illustrated in Fig. 1.

The pipe 39', is connected to an agitating tank, not shown, or to other source of supply of pulp to be fed to the vessel when desired, and to this pipe is attached a branch pipe 42, having a valve 43, which latter pipe is connected with any suitable source of water supply for purposes hereinafter explained. These pipes and their valves are supported by a stand 44, mounted on the bed plate of the machine to hold them rigidly to place.

As is illustrated and above stated, the circumferential walls of the vessel are conical in shape and the circumferential surface of the core member substantially conforms to such shape, furthermore the core is somewhat shorter than the internal length of the vessel, and is not only smaller in diameter than the internal bore of the vessel, but is longitudinally movable therein through movement of its supporting shaft 36.

The diameter of the core is such that when it is moved to its fullest extent to position toward the smaller end of the vessel, as shown in Fig. 1, the annular space 30, being the separating channel, between its circumference and the wall of the vessel, will be of desired comparatively small size or depth, and as the concentrating part of the cycles of operation of the concentrator 130

proceed, the movement of the core toward the larger end of the vessel will increase the depth of such channel to facilitate bedding of concentrates, from the fact that 5 both the vessel and core are conical in form, and when the core is again moved to its initial position, the channel will be again contracted to its initial size.

The longitudinal movements of the core 10 within the vessel are accomplished through longitudinally moving the shaft 36, by traveling it in the hollow shaft 8, and such movement is effected by means of a channeled collar 45, secured thereon, best shown 15 in enlarged detail Fig. 7. The collar is rotatably engaged by a ring part 46, having an attached depending internally screw threaded part 47, engaging a threaded rod 48. The rod is suitably rotatably journaled 20 in a longitudinally fixed position, as illustrated, and carries at its opposite end a gear wheel 49, suitably meshing with a gear wheel 50, which, in turn is mounted on the end of a small rotatably journaled shaft 51. 25 The shaft 51, carries a suitable belt pulley 52, through which rotation may be imparted, so that as the shaft 51 is revolved rotation will be transmitted to the rod 48, through medium of the gear wheels 49 and 30 50, and longitudinal movement of the shaft 36, through the parts 45, 46 and 47 will be secured, resulting in longitudinal movement of the core in the concentrating vessel 35 as above stated, in the one direction or the other as desired, depending on which direction the pulley 52 is revolved.

The pulley 52 is intended to be supplied with power through any of the suitable ordinary reversible transmission devices desired, so its direction of rotation may be reversed at will to meet requirements in 40 operation of the concentrator.

Within the concentrating vessel surrounding the place or zone where the shaft 36 45 enters and in its longitudinal movements travels in and out of the hollow shaft 8, I provide short tube parts 53 and 54, positioned and of size to relatively telescope as the core is moved longitudinally, and serve 50 to protect the adjacent parts of the shafts 8 and 36 from destructive abrasions, which are contained in the pulp being treated in the concentrating vessel.

It will be seen that the protecting sleeve 55 53, is located in the depression at that end of the core, which position is illustrated in Figs. 1 and 4, the depression also serving to enable the sleeve 54 to travel and in operation telescope with the sleeve 53.

These parts are illustrated in relative operating position in Figs. 1 and 6 of the drawings.

In operation, the materials or substances to be separated, composed of particles of 65 different degrees of specific gravity, as cer-

tain metaliferous minerals in ores tailings, and the like, in a comparatively fine state of subdivision and are mixed with water in suitable proportions so that the mixture will preferably be about 20 to 25 per cent. 70 solids, and 75 to 80 per cent. liquid by weight, and which may be termed as pulp, are placed or flowed into any suitable form of agitating receptacle to keep them in suspended mixture while being drawn out for 75 feed to the concentrator. This agitating receptacle or tank is preferably sufficiently elevated above the concentrator so that the pulp will flow by gravity into the concentrator through the feed pipes above explained. 80

During concentration, the vessel is rotated at a high rate of speed to develop the intensity of centrifugal force desired to best assist in effecting separation of the material 85 under treatment.

At the same time the core member is rotated at a sufficiently different rate of speed so that the differential movement of the core with respect to the vessel will create a 90 requisite scouring wash in the concentrating channel to overcome the precipitating effect of the centrifugal force being developed on the particles of waste and other substances relatively lighter than the concentrates, as 95 such substances enter and pass through the separating channel, resulting in these substances being prevented from assuming fixed lodgment, but instead, being carried on through the separating channel by the 100 flow of water, to discharge through the openings 22, and to final discharge through the part 25 of the launder.

The differential movement between the core and concentrating vessel is not intended 105 to be sufficiently rapid so that the resultant scrubbing wash in the separating channel will prevent lodgment of the heavier parts of the material which it is desired to retain as concentrates, but will permit such materials to lodge and progressively bed in the separating channel, while the relatively lighter parts are being scrubbed and flowed through to discharge, as just above explained. 110

Feed of material or pulp for separation is continued until there is a desired quantity of concentrates bedded in the separating channel to largely fill such channel, at which time the feed is stopped by closing the valve 120 40, and the material then in transit through the separating channel will quickly flow on through to waste, or lodge and bed on the separating surface.

The rotating speed of the concentrating 125 vessel is then much reduced by any appropriate mechanism for the purpose, not shown, thereby very much diminishing the degree of centrifugal force being developed to retain the bedded concentrates in the vessel, 130

and clean water is at this time introduced into the vessel through medium of the pipe 42 and valve 43.

The core member is rotated at a constant 5 rate of speed during operation, and at the time the speed of the vessel is much diminished, the differential movement between the two is largely augmented, resulting in a stronger scrubbing wash in the separating 10 channel, which, under the lessened centrifugal force, quickly removes the bedded concentrates, impelling them to discharge through openings 22, where they are caught by the launder 23, in the same manner as 15 the waste materials were caught just previously, and are discharged at the part 25, from which place they may be diverted by any suitable means, to a desired place of deposit.

20 After the bedded concentrates have been discharged from the vessel in this manner, the vessel being cleaned, the vessel is accelerated to its previous speed of rotation for concentration; the flow of clean water is discontinued by closing the valve 43, and feed 25 of material for concentration is again introduced by opening valve 40, and the operation repeated, which may be continued in successive cycles as long as desired.

30 It will be understood that at the beginning of each cycle of concentration the core member is in position nearest the smaller end of the vessel, and during that portion of the cycle in which separation and concentration 35 is occurring, the core is gradually moved toward the larger end of the vessel, by the mechanism above described, so that as the separated concentrates are progressively bedded in the separating channel, this channel 40 is gradually enlarged to permit of such bedding, until the core has reached its extreme position toward the larger end of the vessel.

At this time, the period of unloading the 45 bedded concentrates commences as above explained, and during such period the core is moved to its initial position toward the smaller end of the vessel, preparatory to commencement of another cycle in operation.

50 What I regard as new and desire to secure by Letters Patent is:

1. In a centrifugal concentrator, the combination of a rotatably journaled hollow 55 shaft, a horizontally positioned rotatable separating vessel, mounted on the overhanging end of said hollow shaft, a central shaft, rotatably journaled within the hollow shaft, a core member rotatably supported within the 60 vessel by said central shaft, the core member provided with a longitudinally positioned central sleeve adapted to be withdrawn longitudinally with the core, from its supporting shaft while maintaining the latter in 65 journaled placement, said core forming with

the vessel a separating channel, means for introducing pulp for separation into the vessel and means for discharging the separated pulp from the vessel, substantially as described.

2. In a centrifugal concentrator, the combination of a rotatably journaled hollow shaft, a horizontally positioned rotatable separating vessel embodying a head portion concentrically mounted on the overhanging end of the shaft and a detachable axially extended hollow cylindrical portion provided with an internal separating surface, a central shaft journaled within the hollow shaft and extending into the vessel, a core 75 member rotatably supported within the vessel by said central shaft and adapted to be removed from its said shaft while maintaining the latter in journaled placement, said core forming with the vessel a separating channel, means for relatively differentially rotating the vessel and the core, means for introducing pulp for separation into the vessel and means for discharging the separated pulp from the vessel, substantially as 80 described.

3. In a centrifugal concentrator, the combination of a rotatably journaled hollow shaft, a horizontally positioned rotatable separating vessel, embodying a head portion 95 concentrically mounted on the overhanging end of the hollow shaft, and a detachable axially extended hollow cylindrical portion, provided with a separating surface, a detachable ring interposed between said head and cylindrical portion, a central shaft journaled 100 within the hollow shaft of the vessel and extending therein, a rotatable core member within the vessel mounted on the central shaft, adapted to be removed from said shaft while maintaining the shaft in journaled placement, said core forming with the vessel a separating channel, means for relatively differentially rotating the vessel and the core, means for introducing pulp for separation into the vessel, and means for discharging the separated pulp through said chambered ring from the vessel, substantially as described.

4. In a centrifugal concentrator the combination of a rotatably journaled hollow shaft, a horizontally positioned rotatably separating vessel embodying a head portion concentrically mounted on the overhanging end of the hollow shaft, a detachable internally chambered ring portion mounted on said head and a detachable axially extended hollow cylindrical portion, provided with a separating surface and with a journal bearing at its outer end, having a feed passage therethrough, a central shaft journaled in the hollow shaft of the vessel, and extending therein, a rotatable core member within the vessel mounted on said central shaft and adapted to be removed from said shaft 115

while maintaining the shaft in journaled placement, said core forming with the vessel a separating channel, means for relatively differentially rotating the vessel and core, means for introducing pulp for separation into the vessel, and means for discharging the separated pulp from the vessel through said ring portion, substantially as described.

10 5. In a centrifugal concentrator, the combination of a rotatably journaled hollow shaft, a horizontally positioned rotatable separating vessel embodying a head portion concentrically mounted on the overhanging 15 end of the hollow shaft and a detached cylindrical portion provided with a separating surface, a removable internally chambered ring portion interposed between said head and the cylindrical portions of the vessel, a central shaft journaled in the hollow supporting shaft, a rotatable core member within the vessel mounted on the central shaft, said core forming with the vessel a separating channel, means for introducing pulp 20 for separation into the vessel, means for discharge of material from the vessel embodying holes for discharging separated pulp through the interposed ring, means encircling the vessel in radial alinement with 25 such discharge holes adapted to catch pulp as discharged from the vessel and means for relatively differentially rotating the vessel and the core, substantially as described.

6. In a centrifugal concentrator, the combination of a horizontally positioned rotatably journaled hollow shaft, a rotatable separating vessel, mounted on the overhanging end of said shaft and extended outwardly in axial alinement with said shaft, the vessel provided with a journal bearing attached 40 to its outward end, having a feed opening therethrough, a central shaft rotatably journaled within the hollow shaft of the vessel, and extending into the vessel, a core member substantially shorter than the internal 45 length of the vessel provided with a central depression at its end, and rotatably supported within the vessel by the central shaft, and longitudinally movable within the vessel through medium of its supporting shaft, 50 telescoping members positioned within the vessel in part in said depression in the core members, and around the entrance of the core supporting shaft into the hollow shaft of the vessel, adapted to protect said shaft 55 at such entrance from damaging abrasives, said core forming with the vessel a separating channel, means for relatively differentially rotating the vessel and core, means for longitudinally traveling said core supporting 60 shaft, means for introducing pulp for separation into the vessel and means for discharging separated pulp from the vessel, substantially as described.

WILBUR H. PECK.
